UNITED STATES PATENT OFFICE.

CHARLES W. HUTCHINSON, OF NEW YORK, N. Y.

UNDERGARMENT.

Application filed December 9, 1926. Serial No. 153,669.

This invention relates to undergarments and has particular reference to an improvement in the construction of nether garments such as men's athletic drawers.

One of the principal objects of the invention is to provide a comfortable garment which is rendered especially so by virtue of the manner in which the same is cut and assembled to afford ample crotch and seat room.

The invention furthermore comprehends a nether garment construction which opens at one side to facilitate the donning and removal, which garment is completely closed except for a convenience opening at the lower portion of the front, which opening is normally closed by an inner closure flap.

The invention furthermore comprehends a nether garment which is comparatively simple in its construction, economical to produce, and which is highly efficient in its purpose.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a view of the garment as viewed from the front;

Fig. 2 is a rear view thereof;

Fig. 3 is a vertical sectional view therethrough taken approximately on the line 3-3 of Fig. 1;

Figs. 4 to 10 inclusive are plan views of the various elements which when assembled make up the garment.

Referring to the drawings by characters of reference, A and B represent, respectively, the two rear sections of the garment; C and D the two front sections; E and F the waist-band sections, and G and H the front panel sections. It will be noted that the rear sections A and B are of considerably greater width than the front sections C and D so that a portion I back of the garment when assembled with the front sections C and D, forms a part of the front of the garment at the crotch to render the same more comfortable to the wearer.

In assembling the garment, the edges 11 and 12 of the rear sections A and B are stitched together and the curved edges 13 and 14 of the sections A and B are fitted to and stitched to the straight edges 15 and 16 of the front sections C and D, respectively. It will be noted that the right rear section A is formed with an extension flap J the purpose of which will be hereinafter set forth. The edge 17 of the right rear section A between the points 18 and 19, is stitched to the edge 20 of the right front section C between the points 21 and 22, permitting the extending flap portions K and L of said edges to overlap to provide the side opening. The edge 23 of the rear left section B and the edge 24 of the front left section D are stitched together throughout their length while the edges 25 and 26 of the rear sections and the edges 27 and 28 of the front sections define the lower end of the legs M. The front panel members G and H are applied over a part of the portion I of the combined rear sections at approximately the crotch and over the medial portion of the front sections C and D. The waist-band section E is stitched along its lower edge 29 to the upper edge 30 of the right front section C, the extreme outer end N being provided with a buttonhole O and forming a tab. The remaining waist-band section F is stitched at its lower edge 31 to the upper edge 32 of the left front section D, to the upper edge 33 of the left rear section B, and to the upper edge 34 of the right rear section A, and adjacent its outer end is provided with one or more buttons P with which the buttonhole O of the tab end is adapted to engage. The remaining edge 35 of the rear left section B is unstitched except to the left panel section H so as to define together with the closure flap, the convenience opening Q which is normally closed by the flap J.

From this construction and arrangement, it will be observed that the garment in addition to snugly fitting the waist, hips and legs, affords ample seat and crotch room which renders the garment especially comfortable to the wearer.

What is claimed is:

1. In a nether garment, a pair of rear sections stitched together at the inner edges along a medial substantially vertical line, said rear sections having portions turned upwardly and forwardly, and a pair of front

sections stitched, respectively, to the edges of the upwardly and forwardly turned portions of the rear sections and to the outer edges of the rear sections whereby portions of the rear sections constitute a part of the front of the garment to provide ample crotch and seat room while the upwardly and forwardly turned portions of the rear sections are disconnected to provide a 10 convenience opening.

2. In a nether garment, a pair of rear sections stitched together at the inner edges along a medial substantially vertical line, said rear sections having portions turned upwardly and forwardly, a pair of front sections stitched, respectively, to the edges of the upwardly and forwardly turned portions of the rear sections and to the outer edges of the rear sections whereby portions of 20 the rear sections constitute a part of the front of the garment to provide ample crotch and seat room while the upwardly and forwardly turned portions of the rear sections are disconnected to provide a convenience 25 opening, and a flap on one of said upwardly and forwardly turned sections providing a closure for the convenience opening.

3. A nether garment, including a pair of front and rear sections, each having sub-

stantially straight downwardly divergent 30 inner and outer edges, the latter sections each having an upwardly and forwardly turned elongated inner and lowermost corner defining a gore portion, the outer edges of which gore portions are stitched to the 35 lower portion of the inner edge of the front leg section and the inner edge of which gore portions is stitched to the corresponding edge of the gore portion of the other rear leg section, to provide a garment with 40 ample crotch room.

4. A nether garment, including a pair of front and rear sections, each having substantially straight downwardly divergent inner 45 and outer edges, the latter sections each having an upwardly and forwardly turned elongated inner and lowermost corner defining a gore portion, one of said gore portions being provided with an inner straight edge and the other with an inner convex edge 50 and each of said gore portions having an outer concave edge, the latter concave edge fitted and stitched to the lower portion of the inner edge of the front leg section and the former straight edge stitched to the 55 corresponding convex edge of the other gore portion.

CHARLES W. HUTCHINSON.
